UNITED STATES PATENT OFFICE.

WILLIAM F. MUEHL, OF KANSAS CITY, MISSOURI, ASSIGNOR TO INTERSTATE REFINERIES INC., OF KANSAS CITY, MISSOURI, A CORPORATION OF MISSOURI.

APPARATUS FOR CONVERTING HEAVY HYDROCARBONS INTO LIGHTER HYDROCARBONS.

Application filed July 8, 1921. Serial No. 483,162.

To all whom it may concern:

Be it known that I, WILLIAM F. MUEHL, a citizen of the United States, residing at Kansas City, in the county of Jackson and State of Missouri, have invented certain new and useful Improvements in Apparatus for Converting Heavy Hydrocarbons into Lighter Hydrocarbons; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an apparatus for converting heavy hydrocarbons into lighter hydrocarbons.

20 The invention contemplates the treatment of heavy hydrocarbons whereby the more volatile constituents thereof may be converted into a vapor phase and condensed to a liquid phase to render them adaptable as fuel for hydrocarbon burning engines and the like.

In carrying out the invention, the heavy hydrocarbons, together with the lighter ones, in the liquid phase are preheated by absorbing some of the heat from the lighter hydrocarbons in the vapor phase. This is accomplished by contra-flowing films of mixed heavy and lighter hydrocarbons with respect to previously separated lighter hydrocarbons in the vapor stage, the separated lighter hydrocarbons being subsequently condensed back to the liquid stage so as to be commercially available.

40 A novel apparatus is provided for carrying out the novel method contemplated by my invention, as will be clearly apparent by reference to the accompanying drawings, in which—

45 Fig. 1 is a perspective view of an installation constructed and arranged in accordance with my invention.

Fig. 2 is a vertical, longitudinal, sectional view through one of the filming towers and a preheating tower supported thereby.

50 Fig. 3 is a view partly in elevation and partly in section of a preheating tower and the upper portion of the filming tower.

Fig. 4 is a cross sectional view on the line 4—4 of Fig. 2, and

Fig. 5 is a cross sectional view through a preheater tank and a filming tower associated therewith, part of the tower being shown in elevation.

Referring now to the drawings by numbers of reference:

1 designates a storage tank adapted to communicate with one or more distributing and preheating towers through the medium of a pipe line 2 in which is a cold oil pump 3 for pumping the oil at normal temperature into the tower. The towers are, in effect, heat-exchanging reflux condensers, shown as three in number and designated 4, 5 and 6, superposed upon and supported by the filming towers 7, 8 and 9. The towers 4, 5 and 6, as well as the towers 7, 8 and 9, are all of the same construction one set being shown in Figs. 2 and 3 partly in elevation and partly in section.

The filming tower or towers are shown as supported upon the cover plate 10 of a condenser box 11 and each tower consists of a tubular member 12 provided at its lower end with a constricted sump or reduced portion 13 and at its upper end with an opening 14, communicating with the tubes 15 supported within the tubular casing 16 of a pre-heating tower 4, 5 or 6 as the case may be by the crown sheets or disks 17 and 18 so that communication may be had between the interior of the tube 12 and the outlet 19 at the top of the casing 16, there being a liquid space 20 within the tube 16 surrounding the pipes 15, the space being closed at the top and bottom by the disks 17 and 18. 90

The space or chamber 20 is provided at its top with an inlet pipe 21 communicating in each instance with the pipe 2 and at the bottom of the space 20 is an outlet port or pipe 22, communicating in each instance with the take-off or discharge pipe 23 through the medium of the connections 24 so that oil pumped from the reservoir 1 may pass into the chamber 20 and discharge therefrom through the pipe connections 24 into the pipe 23. The oil passes from the pipe 23 into a preheater tank 25, supported by the furnace setting 26, the construction of the furnace being immaterial but means is pro-

vided therein for raising the temperature of the oil in the tank 25 and after it has reached the proper temperature, for example, 400 degrees F., it will be discharged through the pipe 27 and be pumped into the filming towers by the hot oil pump 28, with the intake of which the pipe 27 communicates.

The discharge end of the pump 28 communicates with a pipe 29, which discharges into the inlet ports 30 of the filming towers 7, 8 and 9, where the oil will be permitted to gravitate over the filming baffles 31 and 32. The filming baffles 31 are shown as comprising perforate disks, the perimeters of which are supported by the interior portions of the walls of the tube 12. The alternating baffles 32 of less diameter, having their perimeters spaced away from the inner walls of the tube 12, are supported by a central tubular member 33, which, in turn, may be supported by the angle 34 at the bottom end of the tower and the angle 35 at the top end of the tower, as clearly seen in Fig. 2. Therefore, oil entering at 30 will pass from the chambered portion 14' through the perforate baffles 31 and over the filming baffles 32, gravitating to the bottom or sump portion 13 where the oil will pass therefrom through the outlet port or ports 36 into the stills 37, supported by the furnace setting 37' provided with suitable heat sources 37" so that the temperature of the oil in the stills 37 can be raised high enough, about 750 degrees F. plus, to volatilize the lighter hydrocarbons or convert them from the liquid phase into the vapor phase, permitting them to accumulate in the dome or domes 38 and pass therefrom through the pipes 39 into the inlet port 40 of the chamber 12' and contra-flow with respect to the oil discharged from the port 30 downwardly. In other words, the vapor entering through 40 will flow in an upward direction and the liquid oil entering through 30 will flow in a downward direction, the gravitating oil absorbing some of the heat of the gases and condensing the heavy hydrocarbons, which will flow along with the oil into the sump 13. The more volatile gases, however, will exhaust through the pipes 15 out through the outlet port 19 and communicate with the manifold pipe 41 through the medium of the pipe or pipes 42 and the branch pipes 43, the branch pipes being connected to the pipes 41 above the valves 44 so that when the valves 44 are closed, the vapor must pass into the pipes 41. If desired, a pressure reducing valve 45 may be placed in each pipe 43.

The vapor will pass from 41 into the distributor pipe 46 in the lower portion of the preheating still or tank 25 so that the vaporized hydrocarbons may escape through the discharge nozzles 47, communicating

with the pipe 46 and bubble up through the heated liquid oil 48 contained in the still or tank 25. The vapor, after passing through the oil 48, will pass into the tower 49, communicating with the upper portion of the still and with the space 50, above the oil 48, the tower being provided with alternating disks 51 and 52, the disks 51 being perforated like disks 31 and the disks 52 being supported by a column or tube 53 like the tube 33 in Fig. 2. Therefore, the vapor will follow a tortuous path within the tower 49 and discharge at the upper end thereof through the outlet port 54, communicating with the pipes 42 below the valves 44 so that the oil in the vapor phase will pass through the condenser box 11 and be converted back into the liquid phase so that the product will be what is known as commercial gasoline.

By reference to the drawings it will be observed that the lighter hydrocarbons in their vapor phase which pass through the tower casing 16 will have some of their heat absorbed by conduction through the medium 90 of the pipes 15 and consequently, the oil in the chamber 20 surrounding said pipes will absorb this heat and be preheated or have its temperature raised above that of the tank 1 from which it was discharged. The oil 95 then passing into the preheater still or tank 25 will have its temperature raised to a considerable degree, approximately 400° F. before entering the tubular member 12, which is the casing for the filming tower, where its 100 temperature will be further raised before it is discharged into the stills 35. While the temperature of the oil in tank 25 is given as 400° F. it is obvious that the actual temperature under operating conditions will vary 105 according to the rate of flow through the tank 25, for example the faster the oil flows the lower the temperature of the oil in tank 25 and vice versa.

The oil, passing downwardly in the tower 110 casing 12, will come in intimate contact with the rising vapors entering the tower casing through the pipe or port 40, consequently, the hydrocarbon liquid will absorb some of the heat from the vapors entering the tower 115 casing through the pipe 40, slightly lowering the temperature of such vapors and permitting the heavier hydrocarbons to condense and precipitate into the sump or receiving chamber 13 before they exhaust 120 through 36 into the still or stills 37, preparatory to having their temperature raised sufficiently to cause the lighter hydrocarbons to be converted into the vapor phase.

There is a special advantage in condensing some of the heavier hydrocarbons in the filming towers 7, 8 and 9 because by so doing, a high grade product will be delivered to the discharge end of the condenser box 11, resulting from the fact that all of the 130

converted hydrocarbons need not be carried off in the vapor phase.

In actual practice I have found that by carrying out my process, I obtain a very high gasoline yield, considerably in excess of the normal yield from stills now generally employed and that the product is marketable without further treatment. For example, gas oil of 30 gravity subjected to 10 125 pounds pressure and 750 degrees F. heat, yields an average of one-half gallon per square foot of heating area per hour with a consumption of two tenths gallons of fuel oil burnt in the furnace per gallon of marketable gasoline.

What I claim and desire to secure by Letters-Patent is:

1. An apparatus for converting heavy hydrocarbons into lighter hydrocarbons comprising a source of oil supply, a heat exchanging reflux condensing tower having a casing at its upper end communicating with the top of the tower, tubes in the casing, crown sheets connecting the tubes to provide an oil chamber about the tubes, the oil chamber having an oil inlet at the top and an oil outlet at the bottom, the oil inlet at the top communicating with the source of supply, a pre-heating still, a pipe connected to the outlet for the oil chamber and discharging into the pre-heating still above the normal liquid level thereof, an outlet pipe communicating with the pre-heating still below the normal liquid level thereof and discharging into the tower below the oil chamber, baffles in the tower below the oil chamber over which the oil from the last named pipe flows, a sump at the bottom of the tower, a main still, a pipe communicating the sump with the main still, a pipe communicating with the main still above the normal liquid level thereof and communicating with the tower above the sump and below the baffles, a vapor conducting pipe connected to the top of the tower above the oil chamber and above the tubes in the oil chamber, a distributor connected to the pipe and located below the liquid level in the pre-heating still, a heat exchanging tower communicating with the pre-heating still, a pipe leading from the top of the last-named tower, a condenser connected to said pipe, the pipe leading from the last-named tower communicating with the pipe leading from the top of the heat exchanging reflux condenser tower to the distributor in the pre-heating still, and a valve in one of the pipes adapted to be unseated so as to by-pass the vapors from the heat exchanging reflux tower directly into the condenser without passing into the pre-heating still.
2. An apparatus for converting heavy hydrocarbons into lighter hydrocarbons comprising a source of oil supply, a heat exchanging reflux condensing tower having a casing at its upper end communicating with the top of the tower, tubes in the casing, crown sheets connecting the tubes to provide an oil chamber about the tubes, the oil chamber having an oil inlet at the top and an oil outlet at the bottom, the oil inlet at the top communicating with the source of supply, a pre-heating still, a pipe connected to the outlet for the oil chamber and discharging into the pre-heating still above the normal liquid level thereof, an outlet pipe communicating with the pre-heating still below the normal liquid level thereof and discharging into the tower below the oil chamber, baffles in the tower below the oil chamber over which the oil from the last named pipe flows, a sump at the bottom of the tower, a main still, a pipe communicating the sump with the main still, a pipe communicating with the main still above the normal liquid level thereof and communicating with the tower above the sump and below the baffles, a vapor conducting pipe connected to the top of the tower above the oil chamber and above the tubes in the oil chamber, a distributor connected to the pipe and located below the liquid level in the pre-heating still, a heat exchanging tower communicating with the pre-heating still, a pipe leading from the top of the last-named tower, a condenser connected to said pipe, the pipe leading from the last-named tower communicating with the pipe leading from the top of the heat exchanging reflux condenser tower to the distributor in the pre-heating still, and a valve in one of the pipes adapted to be unseated so as to by-pass the vapors from the heat exchanging reflux tower directly into the condenser without passing into the pre-heating still.

ing still, a pipe leading from the top of the last-named tower, and a condenser connected to said pipe.

2. An apparatus for converting heavy hydrocarbons into lighter hydrocarbons comprising a source of oil supply, a heat exchanging reflux condensing tower having a casing at its upper end communicating with the top of the tower, tubes in the casing, crown sheets connecting the tubes to provide an oil chamber about the tubes, the oil chamber having an oil inlet at the top and an oil outlet at the bottom, the oil inlet at the top communicating with the source of supply, a pre-heating still, a pipe connected to the outlet for the oil chamber and discharging into the pre-heating still above the normal liquid level thereof, an outlet pipe communicating with the pre-heating still below the normal liquid level thereof and discharging into the tower below the oil chamber, baffles in the tower below the oil chamber over which the oil from the last-named pipe flows, a sump at the bottom of the tower, a main still, a pipe communicating the sump with the main still, a pipe communicating with the main still above the normal liquid level thereof and communicating with the tower above the sump and below the baffles, a vapor conducting pipe connected to the top of the tower above the oil chamber and above the tubes in the oil chamber, a distributor connected to the pipe and located below the liquid level in the pre-heating still, a heat exchanging tower communicating with the pre-heating still, a pipe leading from the top of the last-named tower, a condenser connected to said pipe, the pipe leading from the last-named tower communicating with the pipe leading from the top of the heat exchanging reflux condenser tower to the distributor in the pre-heating still, and a valve in one of the pipes adapted to be unseated so as to by-pass the vapors from the heat exchanging reflux tower directly into the condenser without passing into the pre-heating still.

In testimony whereof I affix my signature.

WILLIAM F. MUEHL.
